TRIVET

Edward G. Beyer, Santa Monica, Calif., assignor to Gamma Associates, Incorporated, a corporation of California

Filed June 9, 1967, Ser. No. 7,420

Term of patent 14 years

(Cl. D44—10)

I claim:

The ornamental design for a trivet, substantially as shown.
